UNITED STATES PATENT OFFICE.

WANTON G. EDDY, OF JASPER, MICHIGAN.

IMPROVEMENT IN CLOTHES-LINE STRETCHERS.

Specification forming part of Letters Patent No. **222,684**, dated December 16, 1879; application filed October 24, 1879.

To all whom it may concern:

Be it known that I, WANTON G. EDDY, of Jasper, in the county of Lenawee and State of Michigan, have invented certain new and useful Improvements in Clothes-Line Stretchers, &c.; and I do hereby declare that the following is a full, clear, and exact description of the invention, which will enable others skilled in the art to which it appertains to make and use the same, reference being had to the accompanying drawings, which form a part of this specification.

Figure 1 is a perspective view, showing a line stretched between three of my improved supports; and Fig. 2 is a detail view of one of said supports.

Similar letters of reference indicate corresponding parts in the figures.

This invention relates to an improved post or support, between two or more of which clothes-lines, hammocks, &c., may be swung; and it consists in the hereinafter-described arrangement of four legs or posts, hinged at right angles to each other to the under side of a disk or plate, three of said legs forming a tripodal support, and the fourth being provided with perforations for the attachment of the clothes-lines, as will be hereinafter fully described, and particularly pointed out in the claim.

In the drawings, A represents a small disk or plate, provided upon its under side with four lugs, B, to which four legs or posts, C D E, are hinged at right angles to each other. The rear post or leg, C, is provided at its lower end with an eye, F, by which it may be

secured to a hook, G, upon a stake, H, which may be driven into the ground in any desired position.

The front leg, E, is shorter than the rest, and is, in practice, extended to an approximately horizontal position. It is also provided with several transverse perforations, I I.

In operation, two, three, or more of the posts are arranged in such a position that the extended legs E shall point toward each other, the rear legs being hooked to the stakes, and the side legs, D D, spread so as to support the posts. Lines J may then be strung through the perforations I, and tightened by simply bringing the legs D of the several posts together.

Between two of my improved posts a hammock may be conveniently swung. To support a clothes-line three or any desired number may be used.

Having thus described my invention, I claim and desire to secure by Letters Patent of the United States—

The plate A, having hinged legs C D D E, the latter of which is provided with perforations I, and the former, C, with an eye, F, in combination with a stake, H, having hook G, as set forth.

In testimony that I claim the foregoing as my own I have hereto affixed my signature in presence of two witnesses.

WANTON G. EDDY.
